UNITED STATES PATENT OFFICE.

GEORGE C. SCHMITZ, OF RACINE, WISCONSIN, ASSIGNOR, BY MESNE ASSIGNMENTS,
TO RICHMOND RADIATOR COMPANY, OF NEW YORK, N. Y., A CORPORATION OF
DELAWARE.

SUCTION CLEANING DEVICE.

1,116,850.

Specification of Letters Patent. Patented Nov. 10, 1914.

Application filed January 30, 1909. Serial No. 475,102.

To all whom it may concern:

Be it known that I, GEORGE C. SCHMITZ, a citizen of the United States, residing at Racine, in the county of Racine and State of Wisconsin, have invented a new and useful Improvement in Suction Cleaning Devices, of which the following is a specification.

My invention relates, more particularly, to suction cleaning-devices of the type containing brush-means at their suction-openings for brushing against the surface to be cleaned during the subjection of said surface to the suction action.

My object is to overcome the disadvantages of prior constructions and to provide a suction cleaning-device of the character referred to which will thoroughly and effectually remove the dust and other particles from the article to be cleaned and in such operation require the minimum amount of power and suction; which shall be compact and positive in operation and shall be sufficiently light in weight to permit it to be readily manipulated for the cleaning purpose by any one desiring to use it, whether in its use it rests upon the floor or is supported in the hands of the operator.

Referring to the accompanying drawings—Figure 1 is a view in side elevation of a suction cleaning-device embodying my invention, the handle thereof being partly broken away near one end. Fig. 2 is an enlarged section taken at the line A on Fig. 4 and viewed in the direction of the arrow. Fig. 3 is a diagrammatic view illustrating by dotted lines the paths of movement traversed by the brush. Fig. 4 is a longitudinal section taken at the line B on Fig. 5 and viewed in the direction of the arrow, the upper end of the casing being shown in elevation. Fig. 5 is a section taken at the line C on Fig. 4, and viewed in the direction of the arrow. Fig. 6 is a face view of the lower portion of the structure illustrated in the preceding figures showing a modification thereof. Fig. 7 is an enlarged view in side elevation of the structure illustrated in Fig. 6, one of the rollers employed being omitted; and Fig. 8, a section taken at the line 8 on Fig. 6 and viewed in the direction of the arrow.

In the embodiment of my invention illustrated, the motor for driving the suction-fan and brush is contained in the head 6 of

the device which, as represented, is in the form of a casing formed with a cylindrical section 7, an expanded, bulged section 8 formed in two parts as represented and having a neck 9, and a relatively flat tapering section 10 secured to the neck 9 and containing an elongated opening 11 at its extremity from which flanges 12 and 13 project to bear against the object to be cleaned. An electric motor, the armature-shaft 14 of which only is shown, is contained in the section 7, this shaft carrying at its outer ends a suction-fan 15 located in the section 8 of the casing. Any suitable form or variety of motor may be employed, wires 16 for conveying the current from the switch 17, which may be connected with any suitable source of electric supply, being shown as extending into the interior of the casing 7 wherein they may be connected with the motor in a well-known manner. The form of fan illustrated is of a well-known type comprising radial blades 18 partially cut away at their central portions, as represented at 19, whereby they join to the hub 20 of the fan.

The section 8 contains an opening 21 in its wall opposite to the fan 15, through which opening the air and dust drawn into the head 8 at its mouth 11 is discharged. Surrounding the opening 21 is an annular rim 22 secured to the section 8 by spacers 23 which hold the rim a slight distance away from the wall of this section. A cloth receptacle 24, in the form of a bag, constituting an air-filter, has an elastic band 25 secured to it at its mouth-portion at which the bag fits over the flange 22 and is releasably held thereon for separating the dust from the air discharged into it from the casing. The bag 24, which preferably is connected at its free end to the handle, as represented, to extend upward, has a lateral enlargement 24^a constituting a pocket formed in its side adjacent to its point of connection with the casing, into which the dust and dirt suspended in the bag under the air pressure therein, falls when rotation of the fan is arrested.

A connector, in the form of a rod 26, extending loosely through an opening 27 in axial alinement with the motor-shaft 14 in a bearing-plate 28 secured crosswise in the head 6, carries a bearing-block 29 at its upper end containing a longitudinally-ex-

tending socket 30 into which the outer ball-equipped end of a pin 31 fixed in the end of the hub 20 and eccentric with the shaft 14, is journaled. The block 29 contains a passage 32 at an angle to the socket 30 into which it opens, an oil-cup 33 fitting in the outer end of the passage 32 serving to supply oil to said socket. The opposite end of the rod carries a clip 34 of spring-metal 5 for releasably holding between its arms 35 a brush-head 36 in position on the shaft 26, the brush illustrated being formed of a stiff back 37 which fits into the clip between its arms, and sets of bristles 38 which extend 15 into the opening 11.

As a preferred means of preventing rattling or vibration of the rod in the bearing afforded by the plate 28, I form, in the face of the latter, a semi-spherical depression 39, into which the rounded end of a bearing-head 40 on the rod fits, this bearing-head being held in place in the depression by a hollow sleeve 41 engaging it and secured to the rod as by a set-screw 42, 25 and a coiled spring 43 surrounding the rod and bearing at one end against the plate 28 and at its opposite end against a collar 44 rigidly secured to the rod 26. The spring 43 serves to hold the head 40 against the 30 bearing surface of the plate 28 at all times, and therefore rattling of the rod 26 at its bearing is prevented.

The motor in rotating not only serves to operate the fan 15 and thereby produce 35 suction at the opening 11, but causes the rod 26, by reason of its eccentric connection with the motor-shaft 14, to move at both ends in a circular path, as represented by the dotted lines 45 and 46, with the result 40 of causing the brush 36 to move through the path represented by the dotted lines 47, and during such movement oscillate from end to end as illustrated by the dotted representation of the brush-head in Fig. 3; it 45 being understood that the degrees of movements of these parts are shown to be somewhat exaggerated in this figure for the purpose of clearly illustrating the action of these parts. These combined movements of 50 the brush as described causes its end-portions to be alternately driven against the object to be cleaned with short sweeping movements, with the effect, when a carpet, cloth, fur, or the like, is being operated on, 55 of causing the bristles to penetrate between the fibers or hairs, as the case may be, and loosen them up and disturb the dust-particles or other particles to be removed from the object being cleaned by the mechanical 60 action of the brush.

It is manifest that by constructing the brush-device in accordance with my invention a relatively small motor may be employed for driving the fan and brush, this 65 feature being of decided importance in a

device of this character, as it renders possible the provision of a device capable of thoroughly and effectually performing the cleaning operation, of such light weight as to permit it to be easily and readily manipulated by the operator. 70

For cleaning uncovered floors, smooth walls, pictures, or like surfaces, the brush may be dispensed with by detaching it from its engagement with the spring-clip, 75 as its employment is not necessary, the suction induced by the fan being sufficient to clean such surfaces.

It is manifest that any other form of motor driven by any other suitable power may 80 be employed and that in so far as certain features of the invention are concerned my invention is not limited to locating the motor in the casing.

In Figs. 6 to 8 inclusive, I have illustrated a modification of the construction shown in the preceding figures, this modified construction affording advantages over the first-described construction, especially where the cleaner is to be operated on fabrics, such as carpets having different lengths of nap, though it affords advantages regardless of the character of the object being operated on, as hereinafter set forth. In this modified construction, the casing 10 is 85 formed on its rear side with a boss 48 containing a horizontal groove 49 in which a rod 50 of resilient material, preferably 90 spring-steel, is confined between its ends by a plate 51 fastened to the boss. The ends 100 of the rod are bent downwardly and outwardly as represented and extend beyond the ends of the casing 10 to afford bearings for rollers 52, the axes of which preferably 105 align with the brush, each roller being provided with rubber treads 53 on which the cleaner rolls upon the articles to be cleaned when it is operated. The operator, by bearing down upon the handle, may cause the 110 bristles of the brush to penetrate the desired 115 distance into the nap, as pressure on the handle causes the rod to flex at its free ends and thus permit the brush and the casing carrying it to be moved toward the object 120 being cleaned. Thus when operating on long nap carpets, where it is desired that the bristles deeply penetrate into the nap, which it will be understood under the 125 suction is caused to stand up from the body-portion of the carpet, the operator will bear down with sufficient force on the handle while moving the cleaner back and forth, to cause the rod to flex at its ends sufficiently far to carry the bristles to the desired position of penetration into the nap; whereas, when a short nap carpet is being cleaned, the pressure exerted on the handle need not be so great as that just referred to, as the purchase of the brush required on the nap where it is short is less than that re- 130

quired where the article operated on has long nap.

The provision of rollers on the device upon which the latter is designed to be rolled across the article being cleaned offers the minimum amount of resistance to the manipulation of the device, regardless of the character of the object being operated on. They furthermore prevent the roughening up of the object being cleaned when it is a fabric or the like lying on a floor, and tend to hold it down flat while being subjected to the suction action.

What I claim as new, and desire to secure by Letters Patent, is—

1. In a suction cleaning device, the combination of suction-creating means, a suction nozzle adapted to be moved over the surface to be cleaned, a vibrating brush operated from the suction-creating means and located in the suction nozzle, and a dust-receptacle.

2. In a suction cleaning device, the combination of suction-creating means, a suction nozzle adapted to be moved over the surface to be cleaned, a brush in the opening of said suction nozzle, and means for rapidly moving said brush bodily into and out of contact with the surface to be cleaned, and a dust receptacle.

3. A suction cleaning device comprising, in combination, a casing containing an opening, means for producing suction at said opening, a brush supported to be operated in said opening against the object to be cleaned, and means for moving said brush through a curved path and simultaneously rocking it from end to end in said opening.

4. A suction cleaning device comprising, in combination, a casing containing an opening, a motor, means for producing suction at said opening, a connector supported between its ends at a bearing in the casing and having eccentric connection at its inner end with the motor-shaft, and a brush at the opposite end of said connector operating in the opening in said casing against the object to be cleaned, for the purpose set forth.

5. A suction cleaning device comprising, in combination, a casing containing an elongated opening, a motor, a suction-fan operated by said motor for producing suction at said opening, a connector having eccentric connection with the motor, a bearing for said connector intermediate the ends of the latter, and an oblong brush connected with said connector and operating in said opening against the object to be cleaned, for the purpose set forth.

6. A suction cleaning device comprising, in combination, a casing containing an opening, means for producing suction at said opening, a motor, a connector having eccentric connection with the shaft of said motor, a bearing for the connector between its ends, and a brush-clamp provided with a removable and replaceable brush-head supported to operate in said opening against the object to be cleaned.

7. A suction cleaning device comprising, in combination, a casing containing an opening, a motor in the casing, means operated by the motor for producing suction at said opening, a bearing, a connector mounted in said bearing and extending longitudinally of the casing and eccentrically connected with the motor-shaft, and a brush on said connector.

8. A suction cleaning device comprising, in combination, a casing containing an opening, means for producing suction at said opening, a brush supported to operate in said opening against the object to be cleaned, means for imparting movement to the brush, means for varying the position of said opening relative to the article being cleaned, comprising a spring-rod connected with said casing, and rollers journaled on the ends of said rod and projecting beyond the ends of the casing on which the device may be moved over the object to be cleaned, for the purpose set forth.

GEORGE C. SCHMITZ.
